OPERATING MECHANISM

Ernest Williams, Pittsfield, Mass., assignor to
 General Electric Company, a corporation of
 New York

Application August 7, 1946, Serial No. 688,884

5 Claims. (Cl. 74—504)

1

My invention relates to improvements in operating mechanisms and especially operating mechanisms for electric switches and the like and particularly for electric switches used in connecting transformers and the like to a source of alternating electromotive force.

When a transformer winding is connected to an energizing source of alternating electromotive force, there is a sudden or transient inrush of magnetizing or exciting current. For a few cycles, this current may be greater than the usual load current. For economy in switching costs, manually operated switches are often provided with only sufficient interrupting capacity to take care of the normal or static magnetizing current. In such cases, if an operator were to close the switch on a transformer and then suddenly open the switch before the subsidence of the transient inrush current, the switch would in all probability be seriously damaged, if not destroyed, and even the operator might suffer personal injury.

An object of my invention is to provide for electric switches and the like an improved operating mechanism such that when a switch is operated to the closed circuit position it cannot be opened until a desired time interval after the closing. Another object of my invention is to provide operating mechanism which can readily be mounted in convenient locations on transformer tanks, radiators and the like. A further object of my invention is to provide an operating mechanism which is economical and simple in both construction and operation and which requires minimum maintenance. These and other objects of my invention will appear in more detail hereinafter.

In accordance with my invention, I provide especially for electric switches and the like an operating mechanism comprising a movably mounted member and means adapted to be operated to move the member in one direction and then to move the member in the reverse direction but only after a desired time interval. Also in accordance with my invention, this means comprises an element secured to the member for movement therewith and an operating lever mounted on the member for movement relatively thereto. Further, I provide means supported on the lever for movement into and out of engagement with one side or the other of a portion of the element and adapted to be moved relatively to the element and the lever to permit movement of the lever independently of the element and then to be moved in the opposite direction to engage the element upon reversal of movement of the lever.

5 My invention will be better understood from the following description when considered in connection with the accompanying sheet of drawings, and its scope will be pointed out in the appended claims.

10 In the accompanying sheet of drawings, Fig. 1 is a vertical elevational view of an operating mechanism embodying my invention with the operating lever shown in one position; Fig. 2 is a sectional view on the line 2—2 of Fig. 1; Fig. 3 is an elevational view similar to Fig. 1 showing the operating lever in a different position; and Fig. 4 is a part sectional view to a larger scale on the line 4—4 of Fig. 1.

15 In the illustrated embodiment of my invention, I have shown an operating mechanism comprising a movably mounted member such as a shaft 1 which may be arranged to operate a circuit controlling member directly or through suitable driving mechanism. The shaft 1 is suitably journaled in a supporting structure 2 which can readily be attached to the pipes of a transformer radiator, for example, by bolts and a backing plate, not shown, or otherwise as will be apparent to 20 those skilled in the art.

25 In accordance with my invention, I provide means adapted to be operated to move the shaft 1 in one direction and then to move the shaft in the reverse direction but only after a desired time interval. As shown, this means comprises an element such as a crank arm 3 which is secured to the shaft 1 for rotation therewith as by means of a pin 4, for example. For actuating the shaft 1, I provide an operating lever 5 which is mounted on the shaft for movement relatively thereto so as to turn about the same axis as the shaft and the arm 3. In the illustrated arrangement, the operating lever 5 is secured to the shaft 1 against longitudinal movement by 30 suitable means such as a retaining washer 6 and a stud 7. The operating lever 5 includes a handle portion 8 which, as shown, is suitably curved for gripping and also offset to provide clearance between the support 2 and the operator's hand.

35 40 45 50 55 In the particular embodiment of my invention illustrated, it is assumed that the mechanism may be operated to actuate a switch for connecting a transformer, for example, to either of two sources of alternating electromotive force indicated as "Line No. 1" and "Line No. 2" and intermediate these positions is a switch open position indicated by "Open." Since it is frequently desired for safety purposes to prevent operation of a switch from a predetermined position, the arm 3 may be provided with a notched segmental

portion 9, the notches of which are arranged for engagement by the bolt 10 of a suitable lock 11 supported, for example, on a flange 12 of the support 2. A resiliently held cover plate 13 may also be provided.

Further in accordance with my invention, I provide means supported on the operating lever 5 for movement into and out of engagement with one side or the other of a portion of the element 3 and adapted to be moved relatively to this element 10 and the lever to permit movement of the lever independently of the element and then to be moved in the opposite direction to engage the element upon reversal of movement of the lever. As shown, this means comprises a pin 14 in threaded engagement with the lever 5 as by a screw 15. The pin 14 is slidably mounted in an opening 16 in the lever 5 directed toward the plane of rotation of the element 3. Thus, by turning the head 17 of the screw 15 associated with the lever 5 and the pin 14, the pin can be moved out of the opening 16 sufficiently to abut one edge or the other of the arm 3 so that movement of the operating lever 5 in one direction effects movement of the arm in the same direction, but movement of the operating lever in the reverse direction will not cause movement of the arm. Thus, before a reverse movement of the arm 3 can be effected, the pin 14 must be retracted into the opening 16, the operating lever 5 moved past the arm 3 in the direction the arm was last moved, and then the pin 14 must be sufficiently projected from the opening 16 firmly to engage the arm 3 when the movement of the operating lever is reversed. The time required to perform this in and out movement of the pin 14 is sufficient for the decay of a transient inrush current to safe switching magnitudes so that an operator after closing the switch to energize the transformer cannot immediately thereafter open the switch on a current above its interrupting capacity as in case of transient magnetizing inrush current.

In some cases, it is desirable to delay the movement of the crank arm 3 through the "Open" position. In such cases, the mechanism may be provided with an intermediate stop device which, as shown, comprises a notched lever 18 pivotally supported on the lower extension 19 of the support 2, as shown more clearly in Fig. 4. In this case, the crank arm 3 is provided with a projection such as a pin 20 which engages the notch 21 on the lever 18 thereby preventing movement of the arm and the lever in one direction, clockwise as shown in Fig. 1. Before further clockwise movement can be effected from the "Open" position to the "Line No. 1" position, the lever 18 must be turned counterclockwise 180° around its pivotal axis which is in line with the pin 20 whereupon the pin 20 is free for movement in the clockwise direction of the crank arm 3. For holding the blocking lever 18 in either one of its blocking positions, the extension 19 is provided with stop pins 22 which are arranged to seat in a depression 23 in the blocking lever.

Assuming that the operating lever 5 has been moved clockwise from the "Line No. 2" position to the "Open" position shown in Fig. 1 and then that the locking lever 18 has been turned counterclockwise from the position shown in Fig. 1 to the position shown in Fig. 3, then the crank arm 3 can be moved to the "Line No. 1" position shown in Fig. 3 by further clockwise movement of the operating lever 5. However, if it is desired to move from the "Line No. 1" position to the "Open" position or to the "Line No. 2" position, then the

screw 15 must be turned in a direction to retract the pin 14 to permit further clockwise movement of the operating lever past the crank arm 3 to the broken line position indicated in Fig. 3. After this has been done, the screw 15 can be turned in the opposite direction to project the pin 14 sufficiently to abut the crank arm 3 on the far edge, whereupon the crank arm can be moved counterclockwise from the position shown in Fig. 3. Operation from the "Line No. 2" position is accomplished in a similar manner.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. An operating mechanism for actuating a movably mounted member of an electric switch and the like in one direction and then actuating the member in the reverse direction but only after a desired time interval comprising an element secured to said member for movement therewith, an operating lever mounted on said member for movement relatively thereto, engaging means supported on said lever for movement into and out of engagement with one side or the other of a portion of said element and adapted to be moved relatively to the element and the lever to permit movement of the lever independently of the element and then to be moved in the opposite direction to engage the element upon reversal of movement of the lever, and means for retarding the movement of said engaging means relatively to said lever whereby to permit the reverse movement of the member only after a desired time interval.

2. An operating mechanism for actuating a rotatably mounted member of an electric switch and the like in one direction and then actuating the member in the reverse direction but only after a desired time interval comprising a crank element rigidly secured to the member, an operating lever supported on said member for rotation relatively thereto, means comprising a projection supported on said lever for movement into and out of abutting engagement with one edge or the other of said element and adapted to be moved relatively to the lever to clear said element whereby to permit rotation of the lever past the element and then to be moved in the reverse direction to engage the element upon reversal of rotation of the lever whereby to move the member in the reverse direction, and cooperating means on said lever and said projection for retarding the movement of the projection relatively to the lever whereby to permit the reverse movement of the member only after a desired time interval.

3. An operating mechanism for turning a shaft in one direction and then turning the shaft in the reverse direction but only after a desired time interval comprising a crank arm rigidly secured to the shaft, a handle lever rotatably mounted on the shaft and provided with an opening toward the plane of rotation of said arm, a pin slidably mounted in said opening, and threaded means associated with said pin and said lever and adapted to be operated to move said pin out of said opening for engagement with one edge or the other of said arm upon rotation of said lever and to withdraw the pin into the open-

ing to clear the arm whereby to permit rotation of the lever independently of the arm.

4. An operating mechanism for turning a shaft in one direction through a predetermined angular range from one position to another position and then turning the shaft in the reverse direction to said one position but only after a desired time interval comprising a crank arm rigidly secured to the shaft, a handle lever rotatably mounted on the shaft and provided with an opening toward the plane of rotation of said arm, a pin slidably positioned in said opening, means adapted to be operated to project said pin from said opening for abutting engagement with one edge or the other of said arm upon rotation of said lever and to retract said pin into said opening to clear the arm whereby to permit rotation of the lever independently of the arm, and cooperating means on said pin and said lever for retarding said projecting and retracting movements of the pin whereby to permit a change in direction of the movement of said member only after a desired time interval.

5. An operating mechanism for turning a shaft in one direction and then turning the shaft in

15

20

25

the reverse direction but only after a desired time interval comprising a crank arm rigidly secured to the shaft, a handle lever supported on the shaft for rotation relatively thereto, and means comprising a pin in threaded engagement with said lever and adapted to be projected therefrom to engage one edge or the other of said arm, said pin being adapted to be turned one way to clear said arm whereby to permit rotation of the lever in one direction past the arm and then to be turned the opposite way to engage the arm upon reversal of movement of the lever whereby to turn the shaft in the reverse direction.
